UNITED STATES PATENT OFFICE.

JOHN C. SCHLEICHER, OF MOUNT VERNON, NEW YORK, ASSIGNOR TO
JOSEPH A. BRITTON, OF NEW YORK, N. Y.

ALARM-BELL.

SPECIFICATION forming part of Letters Patent No. 717,626, dated January 6, 1903.

Application filed October 13, 1902. Serial No. 126,997. (No model.)

To all whom it may concern:

Be it known that I, JOHN C. SCHLEICHER, a citizen of the United States, and a resident of Mount Vernon, in the county of Westchester 5 and State of New York, have invented certain new and useful Improvements in Alarm-Bells, of which the following is a specification.

My invention relates to bells, and especially 10 to those provided with means whereby they may be operated and caused to give an alarm when a door, window, or other movable object is brought in contact with said means. Its objects are, among others, to produce a device 15 of this character of strong and durable construction and certainty of action and of such simple and compact form as to be easily carried about on the person.

To these ends it consists of the combination 20 of parts and arrangements of details hereinafter described and claimed, and illustrated in the accompanying drawings, forming a part hereof.

In the said drawings, Figure 1 is a vertical 25 medial section of a bell attached to an actuating device, which is shown in perspective. Fig. 2 is a horizontal section of the bell immediately below the plane of the plate H of Fig. 1 with the tripping-lever shown in full. Fig. 3 is a like view taken immediately beneath the plane of the plate J. Fig. 4 is a 30 side view showing detached portions of a modified construction of certain parts. Fig. 5 is a plan view of the spring-disk P.

The bell proper and cover A of the bell has 35 a central boss A', having a threaded aperture adapted to receive the threaded upper end B' of the bolt B. This threaded portion is of lesser diameter than the remainder of the bolt, and on the shoulder at the point where 40 the thread commences rests the rotatable spring-disk P, which is held firmly between said shoulder and the boss A'. The main-spring D is suspended beneath the plate J by 45 means of the bolt B, to which one of its ends is secured, and is confined within the arms E, hung upon the sleeve G⁹, surrounding said bolt, the opposite end of the spring being secured to one of the depending ends E' of said 50 arms. The bolt B is rotatably mounted in the plates J and H and has a ratchet F fixed

near its upper end, which is adapted to be engaged by the spring-pawl F', secured to the under side of the plate H. To this plate H the upper ends of the posts upon which the 55 gear-wheels are mounted are secured, and the lower ends are set in the plate or partition J.

The following chain of gear-wheels connects the spring D with the star-wheel S and the escapement N' on the end of the clapper-arm 60 N²: A large wheel G, mounted on the bolt or shaft B, meshes with the pinion G', mounted on the post G⁸. The wheel G², fixed to said pinion, meshes with the pinion G⁵ on the post G⁷, and the wheel G⁶, fixed to the pinion 65 G⁵, in turn meshes with the pinion G⁸ on the post G¹⁰, and thus actuates the star-wheel S, which is mounted on the same post and fixed to said pinion. The clapper-arm N² has a pivot N and is oscillated by means of the escapement 70 N' engaging with said star-wheel S and the clapper or hammer N⁴ on the opposite end thus caused to strike the bell A.

The tripping-lever O extends through the opening C' in the lower casing C of the bell 75 and is pivoted to the pivot-support J', formed by turning up a small portion at the edge of the plate or partition J. A pivot-pin O' passes through the said lever, and the ends of the pivot-support are upset or turned around 80 said pivot. The said pivot-support is mortised out to allow the passage of the lever therethrough. The upper end O² of the lever is bent over and passes underneath the edge of the spring-disk P, which presses upon the 85 said upper end and holds the lever in its normal position. When the lower end of the lever is depressed, it will raise the upper end against the resistance of the spring-disk P, and as soon as the pressure on the lower end 90 of the lever is removed the said spring-disk will return the lever to its position. The clapper-arm N² has a medial upwardly-bent portion of approximately U shape, which brings it into contact with the upper portion 95 of the lever O. It will be seen that the lever O is held in contact with the clapper-arm N² by the spring-disk P and that when the lower end of the lever is depressed the said clapper is released and the ringing of the bell thus 100 accomplished.

The base L is provided with a bottom plate

or shoe M, having its rear end turned downwardly to form a claw M' and its forward end turned downwardly and pointed at the edges to form claws M''. The central portion at the 5 forward edge of the shoe is turned around the pintle R². The lower ends of the spring-plate R are also turned around this pintle, the central portion at this point being cut out to make room for the turned portion M³ of the 10 shoe. A hinge is thus formed for the plate R. The bell is mounted upon the base L by means of the bracket K, bolted thereto, to which the casing C is riveted or otherwise secured, and the portion of the base adjacent to the bell is cut out to make room for the 15 same. The forward upper surface of the base L is inclined in the direction opposite the bell, and the spring-plate R is normally inclined at a slightly-greater angle and 20 extends over the said upper surface of the base. It will be apparent that when the lower point of the base is placed in the path of a door, window, or the like, so that when the same is opened its edge will come in contact with the spring-plate R, the said spring-plate will be depressed and will cause the lever O to release the bell-clapper, thus sounding the alarm. The upturned portion R' at 25 the upper end of the spring-plate R is adapted to check the opening of the said door, window, or the like when it reaches that point, if the same has not already been checked by contact with the upper surface of the base, which 30 acts as a wedge.

35 In Fig. 4 I have shown a modification by which the spring-plate R is dispensed with and the lever O extended downwardly over the inclined upper surface of the base L. In this construction I provide an upwardly-bent 40 portion O⁵, which answers the purpose of the portion R' of the spring-plate, and the extended portion O³ of the lever terminates in the downwardly-turned portion O⁴ within the slot L' near the lower forward end of the 45 base. It will be apparent that the lever will thus be given the desired motion by the opening of the door.

The winding of the spring is accomplished in the usual manner—namely, by rotating 50 the bell, which in turn rotates the shaft or bolt B, secured to the center of the spring. After the spring has been wound and the clapper released the post B remains stationary, while the arms E revolve with the 55 winding of the spring, thus turning the sleeve G⁹, surrounding the bolt B, to which the said arms are fixed, and to the upper end of which the large gear-wheel G is also affixed.

What I claim is—

60 1. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper, and a 65

circular spring-plate in the upper part of the bell secured centrally at the center of said bell and extending in all directions a distance 70 equal to the distance of said arm from said center, adapted to bear down upon the upper end of said arm and hold it normally in contact with the clapper.

2. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper, and a revoluble spring-plate in the upper part of the bell secured centrally at the center of said bell and extending in all directions a distance 85 equal to the distance of said arm from said center, adapted to bear down upon the upper end of said arm and hold it normally in contact with the clapper.

3. The combination of a bell rotatably 90 mounted, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper, and a circular spring-plate in the upper part of the bell secured centrally at the center of said bell and extending in all directions a distance 95 equal to the distance of said arm from said center, adapted to bear down upon the upper end of said arm and hold it normally in contact with the clapper.

4. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper and a circular spring-plate in the upper part of the bell secured centrally at the center of said bell and extending in all directions a distance 100 equal to the distance of said arm from said center, adapted to bear down upon the upper end of said arm and hold it normally in contact with the clapper.

4. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper and a circular spring-plate in the upper part of the bell secured centrally at the center of said bell and extending in all directions a distance 105 equal to the distance of said arm from said center, adapted to bear down upon the upper end of said arm and hold it normally in contact with the clapper.

5. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper and a circular spring-plate in the upper part of the bell secured centrally at the center of said bell and extending in all directions a distance 110 equal to the distance of said arm from said center, adapted to bear down upon the upper end of said arm and hold it normally in contact with the clapper.

5. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper and a circular spring-plate in the upper part of the bell secured centrally at the center of said bell and extending in all directions a distance 115 equal to the distance of said arm from said center, adapted to bear down upon the upper end of said arm and hold it normally in contact with the clapper.

5. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper and a circular spring-plate in the upper part of the bell secured centrally at the center of said bell and extending in all directions a distance 120 equal to the distance of said arm from said center, adapted to bear down upon the upper end of said arm and hold it normally in contact with the clapper.

5. The combination of a bell, striking mechanism inclosed therein comprising a vibratory clapper, a spring and multiplying-gear between said spring and clapper whereby the same is operated, a lower casing inclosing a portion of the said mechanism, an arm extending through said casing having a portion inside the bell adjacent to the clapper and a circular spring-plate in the upper part of the bell secured centrally at the center of said bell and extending in all directions a distance 125 equal to the distance of said arm from said center, adapted to bear down upon the upper end of said arm and hold it normally in contact with the clapper.

center, adapted to bear down upon the upper end of said arm and hold it normally in contact with said clapper, an extended portion of said arm, a base upon which the bell is mounted, an inclined surface on said base over which the arm extends and a slot in said base adapted to receive the outer free end of said arm.

6. The combination of a circular bell, a clamp and actuating means inclosed by the same, a lower casing, a diaphragm closing the upper part of said casing, an opening in said casing and an upturned portion of the diaphragm adjacent to said opening, a tripping arm or lever pivoted to said upturned portion

having one end extending outside the casing and the other extending to the upper part of the bell and a rotatable spring bearing upon the upper end of said arm the outer end of said arm being turned downwardly, an inclined base, and a slot therein into which the said downwardly-turned portion extends. 20

Witness my hand this 30th day of September, 1902, at the city of New York, in the county and State of New York.
